DESIGN FOR A TELEPHONE INDEX

Philip D. Palmer, Toronto, Ontario, Canada

Application December 1, 1941, Serial No. 104,419

Term of patent 14 years

To all whom it may concern:

Be it known that I, Philip D. Palmer, a citizen of the United States of America, residing at 32 Front Street West, in the city of Toronto, Province of Ontario, Dominion of Canada, have invented a new, original, and ornamental Design for a Telephone Index, of which the following is a specification, reference being had to the accompanying drawing, forming part thereof.

In the drawing,

Fig. 1 is an elevational view of one side of a telephone index showing my new design;

Fig. 2 is an elevational view of the opposite side thereof; and

Fig. 3 is an edge view thereof.

The characteristic feature of my design resides, in the telephone index having the configuration shown, in the specific surface ornamentation on the front and back plates thereof, as shown.

I claim:

The ornamental design for a telephone index, as shown and described.

PHILIP D. PALMER.
